ATTORNEY

UNITED STATES PATENT OFFICE

JOSEPH S. JONES, OF BROOKLYN, NEW YORK, ASSIGNOR, BY MESNE ASSIGNMENTS, TO
CHAS. CORY CORPORATION, OF NEW YORK, N. Y., A CORPORATION OF NEW YORK

ANNUNCIATOR

Application filed January 13, 1928. Serial No. 246,619.

This invention is an improvement in annunciating devices, and more particularly in electrically operated reset drops.

One of the primary objects of the invention is the provision of a simple relatively inexpensive drop, particularly resistant to injury by shock.

Another object is to provide a drop of rugged construction, compact, of light weight and efficient in operation under various positions of inclination.

Another object is the provision of a drop requiring a minimum of current for operation.

15 With these and other objects in view the invention consists in the construction and novel combination of parts fully described hereinafter, illustrated in the accompanying drawing, and pointed out in the claims appended hereto, it being understood that various changes in the form, proportion, size and minor details of construction within the scope of the claims, may be resorted to without departing from the spirit of the invention.

20 In the drawing forming a part hereof:—

Fig. 1 is a side view of the improved drop showing the parts in one position.

Fig. 2 is a similar view of a part of the drop showing the parts in another position.

25 Figs. 3 and 4 are end views, looking at the opposite ends of the drop.

Fig. 5 is a diagrammatic view of the wiring.

In the present embodiment of the invention a reset electro-magnet coil 1 is provided, and 30 a set coil 2, the said coils being of usual construction, and arranged coaxially. The center field piece 3 is arranged between the adjacent ends of the coils. At the outer end of the coil 1 is the forward coil head 4, while 35 at the outer end of the coil 2 is the terminal block 5, the head and block being of insulating material, as for instance gray fiber.

A rear field piece 6 is secured to the terminal block 5, in the present instance by 40 screws 7, and the cores 8 and 8a of the coils 1 and 2 are arranged in alinement. A bar 9 is secured below the coil 1, by means of screws 10, or the like. This bar extends beyond the end of the core 8, and curves upwardly to near about the level of the axis of

the cores as indicated at 9a, the free end of the bar being spaced apart from the end of the core 8 as shown.

45 A shaft 11 is journaled in the arm, and the indicator drop is supported by the shaft. This indicator comprises the usual shutter 12, having means indicated at 13 for supporting a name plate 14, and the shutter has a pair of rearwardly extending arms 15, which are secured to the shaft. An armature 16 is secured to the shaft in a fork of the bar 9, and it will be noticed that the armature is of quadrant shape, comprising a body portion extending radially from the shaft, and a tail extending circumferentially of the shaft. The free curved edge of the tail is eccentric to the shaft, so that as the annunciator drop moves into reset position, the curved edge of the quadrant gradually nears the core. 55

50 It will be apparent from the description that when the drop is in the position of Fig. 1, energization of the coil 1, will cause the armature 16 to move into the position of Fig. 2, through the magnetic attraction between the core and the armature, and such movement of the armature will swing the shutter to the position of Fig. 2, that is with its plane substantially parallel with the common axis of the magnets. 60

55 Mechanism is provided for limiting the dropping movement of the shutter to display position, that is to a position where it is substantially perpendicular to the common axis of the coils, and for holding it in the reset position of Fig. 2. This mechanism includes two lateral latch projections 17 from an angular portion 18 on a plate 19, secured at its rear end to an armature block 20 which is hinged to the rear field piece 6, the hinge connection being indicated at 21. 65

60 The portion 18 of the plate is slotted to enable the free movement of the armature 16, and each of the arms 15 of the shutter is cut away on its upper or inner edge, to provide 70 an edge 22 concentric with the shaft 11, and having at one end an elevated stop 23, and at the other a notch 24. The notch and the stop are adapted to be engaged by a projection 17 in different positions of the shutter, 75

as clearly shown in Figures 1 and 2. When the shutter is in the reset position of Fig. 2, the projections are engaged with the notches 24 of the two arms. When the shutter is in display position, the projections engage the stops 23. The latches are operated to release position by the coil 2.

Fig. 5 shows the wiring diagram for the drop. The cores 8 and 8a of the coils 1 and 2 have the usual windings 25 and 26 respectively. Corresponding terminals of the coils, indicated at 27 and 28 respectively are connected to a common lead wire 29. The other terminals 30 and 31 are connected with the positive side of the circuit, the common lead wire being connected to the negative side. The common terminal is indicated at 32, the reset terminal at 33, and the set terminal at 34.

20 The operation of the device is as follows. Normally the shutter is in the position of Fig. 2. When the circuit through the coil 2 is closed, by any suitable mechanism, the core 8a is magnetized, and the bar 20 is lifted to release the latch projection 17 from the notches 24. The upward movement of the projections to release position also acts to start the shutter toward indicating position, through its engagement with the inclined edges 35 on the arms 15.

25 The force exerted by the latch projection is sufficient to start the shutter and gravity does the rest. In order to reset, the circuit through the coil 1 is closed, the circuit of the coil 2 being at this time open. The energization of the coil 25 causes the core 8 to attract the armature 16, and to swing the shutter to the position of Fig. 2. During the movement of the shutter the latch projections 30 ride on the concentric edges 22 of the arms 15, dropping into the notches 24, when the shutter is in reset position.

35 What is claimed as new is:—

1. In an annunciator drop having coaxially arranged setting and resetting magnets, a pivotally mounted drop normally held in reset position against the force of gravity, said drop carrying a shutter, an arcuate armature connected to said drop, means responsive to energization of said resetting magnet to attract said arcuate armature to move the drop with the shutter against the force of gravity into a substantially horizontal position above the pivotal connection of the drop, a latch for holding the drop in such position, and means responsive to energization of said setting magnet for releasing the latch to enable the drop to fall by gravity, the latch and the drop having interengaging means to positively initiate the falling movement of the shutter drop when the latch is released.

2. In an annunciator unit, the combination with coaxially arranged setting and resetting magnets arranged to be mounted for

30 operation in a horizontal position, of a pivotally mounted drop normally held in reset position against the force of gravity, an arcuate armature connected to said drop and movable in a path adjacent said resetting magnet, means operable in response to energization of said setting magnet to cause movement of said drop to display position, and means operable in response to energization of said resetting magnet to attract said arcuate armature and thereby cause a return of said drop to the reset position against the force of gravity.

3. In an annunciator unit, the combination with coaxially arranged setting and resetting magnets arranged to be mounted for operation in a horizontal position, of a pivotally mounted drop normally held in reset position against the force of gravity, an arcuate armature connected to said drop and movable in a path adjacent said resetting magnet, means operable in response to energization of said setting magnet to cause movement of said drop to display position, and means operable in response to energization of said resetting magnet to attract said arcuate armature and thereby cause a return of said drop to the reset position against the force of gravity, said first named means including a mechanism for releasably latching said drop in its reset position.

Signed at New York city, in the county of New York and State of New York, this 11th day of January, A. D. 1928.
